Inventor: Augustus C. Barler,

By Thomas G. Orwig, Attorney

UNITED STATES PATENT OFFICE.

AUGUSTUS C. BARLER, OF FREMONT, NEBRASKA.

HOT-AIR FURNACE.

SPECIFICATION forming part of Letters Patent No. 463,209, dated November 17, 1891.

Application filed February 20, 1890. Serial No. 341,114. (No model.)

To all whom it may concern:

Be it known that I, AUGUSTUS C. BARLER, a citizen of the United States of America, and a resident of Fremont, in the county of Dodge and State of Nebraska, have invented 5 a new and useful Attachment for Hot-Air Furnaces, of which the following is a specification.

My object is to combine an auxiliary radiator and a draft-regulator with a furnace, air-conducting tubes, and an escape-flue in such a manner that the interior of the radiator will be accessible through the draft-regulator, as required, to facilitate cleaning 15 the radiator without detaching or separating any part of the complete device, so that it will be a permanent furnace attachment and fixture in a building adapted to economize fuel and labor in operating a furnace to heat a 20 building.

My invention consists in the construction and combination of an auxiliary radiator and a draft-regulator with a furnace, an escape-flue, and air-conveying tubes in a building, 25 as hereinafter set forth, pointed out in my claim, and illustrated in the accompanying drawings, in which—

Figure 1 is a longitudinal section, and Fig. 2 a transverse section, of the radiator. Fig. 30 3 shows my complete invention applied to a furnace in a building as required for practical operation.

A is a drum of common form, that has open-ended tubes fixed in its top and bottom. 35 B is an open-ended jacket in concentric position with the drum.

C is a tube fixed to the lower end of the jacket to convey cold air.

D is a corresponding tube fixed to the top 40 of the jacket to convey heated air to a room in a building.

E is a pipe fixed in coinciding openings in the upper portion of the drum A and the jacket B to convey products of combustion 45 from a furnace into the drum.

F is a pipe fixed in coinciding openings in the lower portion of the drum and jacket to convey smoke and waste products of combustion from the drum.

H is a draft-regulator of common form on 50 the end of the pipe 2.

By thus combining the drum, the jacket, and the draft-regulator, by means of single straight piece of open-ended pipe, soot or ashes that accumulate in the drum can be 55 readily removed through the open-ended pipe that communicates with the drum.

G is a pipe fixed to the pipe 2 to establish communication with a smoke-flue to carry off the waste products of combustion that enter 60 the drum through the pipe 1, descend in the drum, pass out through the pipe 2, and ascend through the pipe 3 to a smoke-flue L and a chimney.

The different parts may be made of cast 65 metal in molds or of sheet metal, and joined together by seaming, riveting, or in any suitable way to produce an attachment that is complete in itself and well adapted to be readily and advantageously applied to and 70 operated with furnaces of different kinds for heating buildings.

In the practical operation of my invention when applied to a furnace, as shown and described, the calorific that passes with the 75 smoke into the drum is absorbed by the wall of the drum and the open-ended tubes, so that the aggregate area of their inside surface will be a heating-surface and their outsides a radiating-surface from which the calorific 80 will be imparted to cold air that is conveyed upward to envelop the drum, and also to pass into the tubes in the drum to become heated as it ascends inside of the jacket to the tube that conveys it upward into a room 85 in a building.

The draft can be readily regulated in a common way by means of the draft-regulator and the damper.

I claim as my invention—

In an attachment for furnaces, the combination of a drum having open-ended tubes fixed in its top and bottom and having an opening in its upper portion upon one side and another opening in its lower portion 90 upon the opposite side, even with the bottom, an outer shell around the drum open at each end and having means for connecting it with

pipes leading from the cold air to the interior of the room, and also having openings in its sides coinciding with the openings in the drum, a pipe extending through each set of 5 openings, that at the top being adapted to engage with the furnace and the lower one being on a level with the bottom of the drum and having its outer end open and provided with a hinged door, and a vertical pipe com-

municating with the lower pipe between the outer end and the outer casing and adapted to engage with a pipe leading to the chimney, substantially as described.

AUGUSTUS C. BARLER.
